(57) **CLAIM**

The ornamental design for a vehicle wheel disc, as shown and described.

DESCRIPTION

FIG. 1 illustrates a front perspective view of a vehicle wheel disc;

FIG. 2 illustrates a rear perspective view of the vehicle wheel disc of FIG. 1;

FIG. 3 illustrates a front elevational view of the vehicle wheel disc of FIG. 1;

FIG. 4 illustrates a rear elevational view of the vehicle wheel disc of FIG. 1;

FIG. 5 illustrates a left side elevational view of the vehicle wheel disc of FIG. 1;

FIG. 6 illustrates a top view of the vehicle wheel disc of FIG. 1;

FIG. 7 illustrates a cross-section of the vehicle wheel disc of FIG. 1 taken along line 7-7 in FIG. 3; and,

FIG. 8 is a detailed view of region 8 in FIG. 3.

The broken lines in the drawings are for the purpose of illustrating portions of the vehicle wheel that form no part of the claimed design. The dot-dash broken line circles depict the limits of the enlarged views and form no part of the claimed design.
